MUFFLER-TYPE TOY

Strohm Newell, Los Angeles, and Lew Fay,
Burbank, Calif.

Application December 1, 1949, Serial No. 130,378

2 Claims. (Cl. 46—175)

1

This invention relates to a muffler-type toy adapted to be used on vehicles such as for example bicycles, tricycles, and other children's toy vehicles.

A primary object of the invention is to provide a device that may be readily applied to a child's vehicle so as to be driven thereby in the course of movement of the vehicle and which will create a sound simulating the exhaust through the muffler of a motor-driven vehicle. Many children possessing leg-driven vehicles or even gravity propelled vehicles desire to have the vehicles create such sound simulating a motor-driven vehicle even though their vehicles are not so equipped. The present device is designed to fulfill such desires.

More specifically, an object of the invention is to provide a muffler-type toy consisting essentially of an elongated tube providing a type of resonance chamber, one end of which is closed by rubber or a rubber substitute in which a reed is embedded so as to project into the chamber formed by the tube the projecting end being engageable by a star wheel driven as the vehicle progresses so as to cause the reed to be vibrated to simulate the sound emanating from the muffler of a motor-driven vehicle. By having the reed thus embedded in rubber or rubber substitute at an end of the resonance chamber the desired sound may be produced in contrast with a structure wherein the reed is mounted on a wall of the metallic tube. In such constructions, the sound produced is objectionable in that it is quite tinny whereas a muffed sound is desirable.

Still another object of the invention is to provide a toy of this character applicable to bicycles, tricycles, and the like which can be easily installed without modifying or altering the construction of the bicycle or the tricycle as the case may be and which is so designed that it may be optionally rendered inoperative.

With the foregoing and other objects in view, which will be made manifest in the following detailed description and specifically pointed out in the appended claims, reference is had to the accompanying drawings for an illustrative embodiment of the invention, wherein:

Figure 1 is a view in side elevation of a bicycle illustrating the toy embodying the present invention in applied position thereon;

Fig. 2 is a horizontal section on an enlarged scale taken substantially upon the line 2—2 upon Fig. 1;

Fig. 3 is a view similar to Fig. 2 but illustrating the device in that position wherein it is rendered inoperative;

2

Fig. 4 is a partial view in side elevation taken substantially upon the line 4—4 upon Fig. 2, in the direction indicated;

Fig. 5 is a partial view in vertical section taken substantially upon the line 5—5 upon Fig. 2 in the direction indicated;

Fig. 6 is a partial view in vertical section taken substantially upon the line 6—6 upon Fig. 2; and

Fig. 7 is a view similar to Fig. 5, but illustrating a slightly modified form of construction.

Referring to the accompanying drawings wherein similar reference characters designate similar parts throughout, the device embodying the present invention is illustrated as having been applied to the conventional bicycle, generally indicated at B on Fig. 1. The conventional bicycle has a pedal-driven driving sprocket 10 mounted thereon which drives a smaller driven sprocket 11 on the rear wheel thereon through a chain 12. Conventionally, both of these sprockets are mounted on the right-hand side of the bicycle. The toy embodying the present invention is preferably mounted on that end of the axle 13 for the rear wheel of the bicycle opposite the driven sprocket 11. It consists essentially of a thin-walled metal tube 14 of suitable length, the forward end of which is closed by rubber or rubber substitute 15. The rear end of the tube may be beveled off as indicated at 16. Within the rubber closure 15 there is disposed a metal reed 17 which is preferably vulcanized directly in the rubber 15. This reed may be apertured as at 18 so that in the course of molding the closure 15 to shape the rubber stock may pass through the apertures to firmly anchor the reed 17 therein. The closure 15 can be fastened in the forward end of the tubing 14 by spinning the forward edges inwardly as indicated at 19. The reed projects rearwardly within the tube 14 a short distance so as to be engageable with a star wheel 20 that is rigidly mounted on a spindle 21 that extends transversely through the tube 14 adjacent its forward end. The side walls of the tube are preferably merely pierced so that the inwardly bent edges of the holes that accommodate the spindle 21 form inexpensive bearings therefor indicated at 22. That end of the spindle 21 that extends toward the rear wall of the bicycle carries a pinion 23 which may be secured to the spindle such as by riveting the end of the spindle as indicated at 24. Any other means may be employed to rigidly secure the pinion to the spindle. A coil compression spring 25 is disposed between the tube 14 and the pinion 23 and urges the spindle toward the bicycle, such movement being limited by the head 26 on the

spindle engaging the opposite wall of the tube 14. A gear 27 is provided which consists of a sheet metal disc applicable over the end of the axle 13 and which carries ears 28 through which bolts 29 may be extended to clamp the gear on the spokes of the rear wheel in concentric relationship to the axle 13. This gear is preferably formed by merely striking out of the body of the disc projections 30 which provide teeth that mesh with the teeth on the pinion 23. A bracket 31 is riveted or spot welded to the tube 14 adjacent its forward end and is slotted as indicated at 32 to receive the end of the axle 13. This bracket may be either interposed between the nut on the end of the axle and the bicycle frame, or if the axle 13 is of adequate length it may be slipped onto the end of the axle and an additional nut and washer provided to rigidly mount the tube 14 in a substantially horizontal position extending rearwardly from the rear axle. The bracket is so mounted on the tube 14 that when the device is installed on a bicycle it will not ordinarily interfere with the braces for mud guards if the bicycle is so equipped.

As the bicycle progresses its rear wall which constitutes a ground wheel thereof on rotating rotates the gear 27 therewith which drives the pinion 23 and thus rotates the spindle 21 and the star wheel 20. The star wheel, while in engagement with the reed vibrates the reed 17, causing a sound to issue from the tube 14 that is quite similar to the sound issuing from the muffler of a motor driven vehicle. The fact that the reed is out of direct contact with the tube 14 but is embedded in the rubber closure 15 brings about the desired type of muffled sound. If the reed 17 were so mounted as to be in direct contact with the metallic tube 14 or with a metallic end closure for the tube, the sound produced would be of a tinny character which would not adequately resemble the sound issuing from the muffler of a motor driven vehicle.

It is desirable to be able to disengage or render the toy inoperative without disassembling it or removing it from the bicycle. To this end, the compression spring 25 enables the spindle 21 to be axially shifted a sufficient distance to disengage the pinion 23 from the gear 27. The outer wall of the tubing 14 has a latch 33 pivotally mounted such as by bolt 34 and this latch may assume either of the two positions illustrated in Fig. 4. When the latch is in the full-line position the spring 25 is effective to maintain the spindle 21 in that position wherein the pinion engages the gear. On the other hand, if the spindle 21 is forcibly shifted in opposition to the compression spring 25 the latch may be swung into the full-line position shown in Fig. 3 and dotted line position shown in Fig. 4, wherein it occupies a position between the head 26 and the tube 14 holding the pinion 23 out of engagement with the gear 27. In this position the bicycle may be ridden without causing the toy to function or operate. Reverse swing of the latch enables the compression spring 25 to reengage the pinion 23 with the gear 27.

It is, of course, possible to mount the improved toy on the right-hand side of the vehicle and equip the pinion 23 with a rubber tire which will engage the chain 12 and sprocket 11 on the right-hand side. This arrangement, however, is not preferred due to the fact that most bicycles are either equipped with coaster brakes or overrunning clutches enabling the bicycle to coast without involving a rotation of the sprocket 11 or

movement of the chain 12. By mounting the toy on the bicycle in the position shown, the device will continue to function whether the bicycle is coasting or not.

5 In Fig. 7, a slight modification is illustrated wherein the closure 15a for the forward end of the tubing has been cored out as indicated at 15b around the location where the reed 17a is anchored. This arrangement permits the closure to be made without employing as much rubber stock and to some extent enables the anchoring of the reed to be made somewhat more resilient.

15 From the above-described construction it will be appreciated that an improved muffler-type toy has been provided which is readily applicable to children's vehicles so as to be driven thereby and which will produce a sound closely resembling the sound produced from the muffler of a motor driven vehicle.

Various changes may be made in the details of construction without departing from the spirit and scope of the invention as defined by the appended claims, wherein:

We claim:

1. A device of the class described comprising a tube, a rubber closure for one end of the tube, a reed anchored on said closure and projecting therefrom into the tube, a spindle rotatably mounted on the tube, a star wheel on the spindle engageable with the reed, a pinion on the spindle on the exterior of the tube and a gear applicable to a wheel of a child's vehicle for meshing engagement with the pinion enabling the star wheel to be driven thereby, said spindle being axially adjustable, spring means urging the spindle into that position wherein the pinion will engage the gear, and means for latching the spindle in a position wherein the pinion and gear are mutually disengaged.

40 2. A device of the class described comprising a tube, a rubber closure for one end of the tube, a reed anchored on said closure and projecting therefrom into the tube, a spindle rotatably mounted on the tube, a star wheel on the spindle engageable with the reed, a pinion on the spindle on the exterior of the tube and a gear applicable to a wheel of a child's vehicle for meshing engagement with the pinion enabling the star wheel to be driven thereby, said spindle being axially adjustable, spring means urging the spindle into that position wherein the pinion will engage the gear, said spindle having a head thereon adjacent one side of the tube and a latch pivotally mounted upon said side of the tube 45 being adapted to be swung into a position between the head and the tube to hold the spindle in a position wherein the pinion and gear are mutually disengaged.
